(57) **CLAIM**

The ornamental design for a portion of a wheel loader, as shown and described.

DESCRIPTION

FIG. 1 is a left side view of a portion of a wheel loader showing my new design;

FIG. 2 is a right side view thereof;

FIG. 3 is a top plan view thereof;

FIG. 4 is a front view thereof;

FIG. 5 is a rear view thereof; and,

FIG. 6 is a left rear perspective view thereof.

The broken lines of the figures showing additional portions of the wheel loader are included for the purpose of illustrating environmental structure and form no part of the claimed design.
